(57) **CLAIM**

We claim the ornamental design for a perforated hole pattern for a vehicular seat, as shown and described.

DESCRIPTION

FIG. 1 is an enlarged plan view showing a repeating square arrangement of a perforated hole pattern for a portion of a vehicular front seat;

FIG. 2 is a further enlarged plan view, taken within rectangle 2 of FIG. 1, showing a repeating square arrangement of the perforated hole pattern; and,

FIG. 3 is a further enlarged plan view, taken within circle 3 of FIG. 1, showing a repeating square arrangement of the perforated hole pattern.

The broken lines are for illustrative purposes only and form no part of the claimed design. The repeating square arrangement of perforated holes in the flexible seat cover material is part of the claimed design.
